(57) **CLAIM**

The ornamental design for a storage system for index cards and the like, as shown and described.

DESCRIPTION

FIG. 1 is a top view of one embodiment of the storage system of the present invention with the flaps closed and wherein the storage system is made of a transparent material;

FIG. 2 is a top view of the storage system of FIG. 1, with the flaps open;

FIG. 3 is a front perspective view of the storage system of FIG. 1 positioned in a notebook;

FIG. 4 is a front perspective view of the storage system of FIG. 3 with the flaps open;

FIG. 5 is a top view of the another embodiment of the storage system of the present invention with the flaps closed and wherein the storage system is made of an opaque material;

FIG. 6 is a top view of the storage system of FIG. 5, with the flaps open;

FIG. 7 is a front perspective view of the storage system of FIG. 5 positioned in a notebook; and,

FIG. 8 is a front perspective view of the storage system of FIG. 7 with the flaps open.

The broken lines are for environmental purposes only and do not represent any part of the claimed design.

The remaining views of the storage system for index cards and the like are merely duplicative of other views or are flat and include no ornamentation.
